PACKING MACHINE FOR NURSERY STOCK
Robert J. Broersma, Spring Lake Township, Ottawa
County, Mich., assignor to B & B Engineering Com-
pany, Grand Haven, Mich., a partnership
Filed Dec. 7, 1962, Ser. No. 243,044
15 Claims. (Cl. 53—124)

This invention relates to the packing of irregular articles and it particularly relates to the packing of nursery stock into packages for storage, handling and merchandising.

While the subject matter of the present invention is applicable to a wide range of articles and situations, it developed out of a need in the nursery packaging field and accordingly the hereinafter presented description will be carried out in terms of the needs and practices of nursery operations. However, it will be clearly understood that reference to such features hereinafter is solely for descriptive purposes and not limiting.

Turning now to the requirements of a packing machine useful in the nursery field for illustrative purposes as above set forth, it has long been a problem to handle nursery stock, particularly relatively small stock, in large quantities, wrapping same in a moisture-controlling material, such as peat moss, and then inserting same into a suitable storage and/or merchandising package. Much of this nursery stock is of a relatively delicate nature, has fine and completely flexible roots so that it is sufficient if it is merely laid onto a moisture-controlling material, and the same wrapped about the roots of the plant. While the problems of filling the packing material in and among the roots of large and stiff nursery stock, such as is dealt with in my application Serial No. 185,915, now Patent No. 3,195,283, are not of concern here, the problem of minimizing root damage dealt with therein is not only present here also but is even more important here since the kinds of nursery stock handled in the situation here being considered are often relatively delicate and if treated at all roughly will be unduly damaged. Such damage may affect the capacity of growth or it may affect only the appearance but in even the latter event it will render the merchandise less attractive for sale.

While such products can be packaged in relatively large numbers reasonably inexpensively by hand methods, there still remains the problem of insuring uniformity of packing when same is done by hand. Further, when such packaging is done by hand and it becomes necessary to package several hundred thousand nursery units within the space of a few weeks, it often requires very large expansion of the labor force of a given nursery. This presents hiring and other personnel problems and also presents problems of providing working space for a large number of people for only a few weeks of time. All of these represent multiplying and interrelated problems in large nursery operations which it is desired to minimize and which is possible by the substitution of machine handling of such nursery stock in place of hand handling thereof.

A further problem in the packing of nursery stock lies in the many different sizes, shapes and conditions under which such material is to be packed. Some nursery stock has relatively limp structure so that it can be readily protected merely by folding it into any kind of packing material, whereas other stock, such as shrubs and roses, may have a stiff root structure whose conditions of packing are somewhat different. Other situations recognize the fact that nursery stock needs to be packed in a variety of different materials. For example, peony roots are required to receive water and hence are packed into a moisture-holding material, such as peat moss. Other roots, such as canna, are required to be kept dry and hence are packed into moisture-absorbing material, such as wood shavings.

2

Further, some nursery stock is packaged in sacks, some in boxes, and others in pots. To provide different machines for the handling of even a substantial number of these different situations and the various combinations thereof has long been recognized as desirable but considered impossible and, to my knowledge, not successfully accomplished prior hereto.

Finally, it must be recognized that any machine for packing nursery stock or similar is likely to be operated by labor unskilled in the operating of machines. Similarly with respect to maintenance, it must be recognized that a machine which could be properly maintained by the personnel available in a machine shop employing skilled machinists would not be suitable in a nursery where it is not likely that any of the personnel will be skilled machinists. Hence, for this further reason, previously designed automatic machines for this purpose have not, insofar as I am aware, been commercially successful.

Accordingly, the objects of the invention include:

20 (1) To provide a method for packing irregularly shaped articles in a mass of soft material which can be carried out by a variety of different mechanical devices and which will be applicable to articles of a variety of different shapes and sizes.

25 (2) To provide a method, as aforesaid, which is particularly adaptable to the packing of nursery stock, which will be capable of use with many different kinds, sizes and types of nursery stock and, which will be capable of packing same in many different kinds and sizes of containers.

30 (3) To provide a method, as aforesaid, which can be practiced by apparatus which is of relatively simple construction whereby to minimize both costs of construction and cost of maintenance.

35 (4) To provide apparatus capable of carrying out the foregoing-named objectives.

40 (5) To provide apparatus, as aforesaid, which will be operable with nursery stock of many different types including both those having soft or limp structures and those having relatively stiff root structures and wherein a given machine may be readily used with several different types of containers or packages with little or no physical modification thereof.

45 (6) To provide apparatus, as aforesaid, which can be manufactured as a single unit or wherein such units can with only slight modification be arranged in multiple for high-speed automated operation.

50 (7) To provide apparatus, as aforesaid, which will be of sufficient simplicity as to be capable of manufacture at a relatively low cost and which is further of sufficient simplicity as to be capable of maintenance at a low cost and by personnel which is relatively unskilled mechanically.

55 (8) To provide apparatus, as aforesaid, which can be automated, if desired, but automated to a variety of different degrees of automation whereby a given base structure may be provided with whatever controls and auxiliary equipment is best suited to a given user's requirements.

60 (9) To provide apparatus, as aforesaid, which will impose no appreciable danger onto the operators.

Other objects and purposes of this invention will be apparent to persons acquainted with a device of this general type upon reading the following specification and inspection of the accompanying drawings.

General description

In general the invention comprises a method wherein a body of packing material, such as peat moss or wood shavings is held in a generally horizontal position and the article to be packed is placed thereon. The packing material is then folded around such article and held by suitable means. The material is next pushed out of the holding means without disturbing its relationship to the article packed therein, usually into and through a suitable guide and thence into the desired receptacle.

In the preferred apparatus for carrying out this process, the material is received into a pair of hemicylinders which are hinged together and the article, such as a nursery plant, is laid on top of the packing material. The hemicylinders are then brought together to define a cylinder whereby the packing and the plant are held firmly with respect to each other. A ram which is slotted to permit it to contact the packing material without appreciably contacting the plant, is caused to bear against the packing material, push same out of said closed hemicylinders, into and through a suitable guiding tube and thence into the receptacle. When the device is to be made into an automatic machine, a plurality of packing units as just described is arranged on one conveyor belt with suitable means operating the parts thereof and a plurality of cooperating receptacles is carried on another conveyor device adjacent the several discharge points of said packing units.

Detailed description

In the following description, certain terminology will be used for convenience in reference which will be recognized as for convenience only and as not limiting. For example, the terms "rightward" and "leftward" will refer to directions to the right or left as appearing in the drawings in connection with which such terminology is used. The terms "upward" and "downward" will refer to directions with respect to the apparatus in its normal position of use. The terms "inward" and "outward" will refer to directions toward and away from the geometric center of the apparatus.

Such terminology will also include derivatives of said words above mentioned as well as words of similar import.

Referring first to the single-station form of the apparatus, there is provided a table 1 supported on any convenient frame indicated only schematically at 2 and 3, the same being arranged to stand upon the floor or any convenient support. Supported upon said table is a plate 4 which in turn supports an inverted channel member 8 whose flanges are affixed to the plate 4, such as by welding. A pair of end plates 9 and 11 are affixed to the opposite ends of said channel 8 and extend upwardly therefrom.

A pair of hemicircular casing members, here halves 12 and 13 are arranged between the end supports 9 and 11 and are fastened together by a continuous hinge member 14 at the mutually adjacent lower edges thereof. Thus, said casing members 12 and 13 may be moved from an open position as shown in FIGURES 3 and 5 to closed position where same define a cylinder as shown in FIGURES 1, 2 and 4.

An convenient means may be provided for moving said casing halves between open and closed positions, but one convenient device for this purpose is the yoke 16 (FIGURES 1, 4 and 5). Here there is provided an opening 17 extending through the web of the channel member 8 and through said opening there extends a guide casing 18. Said guide casing is fixed rigidly with respect to the channel 8 in any convenient manner, such as by a pair of bracket plates 19 and 20 (FIGURE 1) which are each fastened to said guide casing 18 and further fastened to the channel 8. A pair of slots 22 and 23 (FIGURE 4) are provided on opposite sides of the guide casing 18 transversely of the axis of the cylinder formed by the casing halves 12 and 13 when they are in closed position. A push rod 24 is affixed rigidly to a pair of arms 26 and 27 to constitute the Y-shaped yoke 16, said push rod extending telescopically within the guide casing 18 and said arms extending laterally through the slots 22 and 23. Rollers 28 and 29 are preferably, but not necessarily, affixed to the ends of the respective arms 26 and 27. An opening 31 is provided through the table 1 for permitting the guide casing 18 and parts associated therewith to extend to a point below said table if desired.

Any convenient means for urging the casing halves 12 and 13 into open position may be provided which in this instance constitutes an elastic member 32, such as either a coil spring or a piece of shock cord. Thus, upward movement of the yoke 16 will effect closure of the casing halves 12 and 13 and downward movement of said yoke will permit the elastic element 32 to effect opening of 50 and casing halves.

An opening 33 (FIGURE 8) is provided through the end plate 9 of approximately the same size and coaxial with the interior diameter of the cylinder formed by the casing halves 12 and 13 when same are closed with respect to each other and a guide cylinder 34 is affixed rigidly to the end member 9 and coaxial with said opening 33. The leftward or discharge end of said guide member 34 may be shaped in any of many ways for facilitating the discharge of packed material from said guide member to a bag or other container indicated in broken lines at C.

A generally U-shaped opening 36 (FIGURES 4 and 5) is provided in the end member 11 extending through the upper edge thereof with the lower edge 37 (FIGURE 5) defining an arc substantially coaxial with the lower part of the casing halves 12 and 13 when same are in their closed position. A pusher 38 is provided with a radius slightly smaller than that of the arc 37 by nevertheless capable of clearing same only slightly as is reciprocates and thereby passes through the end member 11. Said pusher 38 may, if desired, be of the multipart construction here shown wherein a face plate 66 (FIGURE 6) is removably secured to a coaxial backing plate 67 by any convenient means such as screws 68. The backing plate 67 is secured by brackets 69 to a rod 41. The

5

face plate 66 is provided with an upwardly opening slot 39 the lower edge of which defines an arc of radius slightly larger than the radius of the stem of the plant to be packed and substantially coaxial with the face plate 66 itself and extending through the upper edge thereof. The backing plate 67 is provided with a similar but larger slot 70. The rod 41 is mounted on a slide 42 and said slide 42 reciprocates on a guide member 43 which is supported by brackets 44 and 46 rigidly on the table 1. The rod 41 is reciprocated by any convenient means, such as a plunger 48 of a suitable pressure fluid cylinder 47. Preferably, said pressure fluid cylinder will be an air cylinder but this is a matter of choice.

The rod 24 of the yoke 16 may be vertically urgeable in any convenient manner, such as by means of a pressure fluid cylinder 51 connected to said rod. Thus operation of the cylinder 51 in one direction will push the yoke 16 upwardly to close the casing halves 12 and 13 in the manner shown in FIGURE 4 and operation of the cylinder 51 in another direction will permit the rod 24 to move downwardly in part by gravity and in part by the response to the urging of the resilient member 32. to permit the opening of said casing halves.

Any convenient hopper means 50 (FIGURE 5) may be provided above the casing halves 12 and 13 and same may be operated either manually or automatically for dispensing packed material into said casing halves when desired. In the embodiment illustrated in FIGURES 1 to 5, the hopper is provided with an opening 54 through which a reciprocating trap device 53 is extendable. Said trap 53 is provided with a portion 56 for defining a measured quantity and a solid shuttle 57 for closing the opening 54 when same extends therethrough. A pressure fluid cylinder, such as an air cylinder 58 is provided for reciprocating said trap. While any of convenient responsive means may be used, a pressure fluid switch 59 is here provided to be actuated by the slide 42 when same is in its retracted position (rightward in FIGURE 1) whereby to energize the cylinder 58 for conveying packed material from the hopper 50 into the casing halves 12 and 13 when same are in their open position. A second pressure fluid switch 60 is provided for operation when the yoke 16 is in its upward position by which to energize the cylinder 47 and cause plunger 48 to move leftwardly (as seen in FIGURE 1) for purposes as set out further hereinafter.

FIGURE 17 discloses for purposes of illustration a preferred hydraulic control device by means of which the cylinders 47, 51 and 58 may be operated in a predetermined sequence with a minimum of effort on the part of the operator. The source S of pressure fluid, which is preferably compressed air, and which will be referred to as such hereinafter, feeds through appropriate filters, a pilot feeder regulator R₁ which in turn feeds the pilot valves V₁, V₄, V₆ and V₇. The pilot valve V₁ is opened by means of a push-button PB₁ and when so actuated allows air from the pilot line to flow therethrough to the pilot valve V₂. The pilot valve V₂ is opened by means of the push-button PB₂ and when so actuated allows air to flow therethrough to the air cylinder AC₁. The pilot valves V₁ and V₂ are biased in their closed position by the springs S₁ and S₂, respectively.

The source S also feeds through the main line regulator R₂ and lubrication device L to the main valves V₃, V₅ and V₈. The main valve V₃ is actuatable leftwardly from the position of FIGURE 17 by said air cylinder AC₁ to admit air from the main line to the lower chamber of the air cylinder 51 and to allow the upper chamber of said air cylinder 51 to exhaust into the atmosphere thereby moving the piston rod of the air cylinder 51 upwardly.

The air switch 60 of FIGURE 1 is seen in FIGURE 17 to be comprised of the pilot valve V₄, a spring S₄ and a cam C₁. The pilot valve V₄ is actuatable to its open position by means, such as the cam C₁, actuated by the

rod 24 (FIGURE 1) as same reaches its uppermost position, said rod 24 being driven by the piston rod of the air cylinder 51. The pilot valve V₄ (FIGURE 17) is biased toward its closed position by the spring S₄. The valve V₄ in its open position allows air to flow from the regulator R₁ to an air cylinder AC₂ and to a timing device T₁.

Actuation of the air cylinder AC₂ moves the main valve V₅ leftwardly to allow air from the regulator R₂ to flow into the leftward side of the air cylinder 47 and to allow the rightward side of the air cylinder 47 to exhaust into the atmosphere thereby driving the pusher 38 (FIGURE 1) into the cylinder defined by the casing halves 12 and 13. The main valve V₅ is biased against such leftward movement thereof by a spring S₅.

The timing device T₁ is comprised of a restrictive orifice 201 and a ball check valve 202 in parallel therewith. Said ball check valve 202 is oriented to prevent air flow therethrough from the pilot valve V₄. The timing device T₁ provides a time delay which may conveniently be adjustable and which delays the actuation of an air cylinder AC₃ fed thereby for a predetermined interval after the actuation of the air cylinder AC₂. The air cylinder AC₃ moves the pilot valve V₆ leftwardly against a spring S₆ to open said valve and to thereby allow air from the regulator R₁ to flow to air cylinders AC₅ and AC₄.

Actuation of the air cylinder AC₄ moves the main valve V₃ rightwardly thereby allowing air from the main regulator R₂ to flow into the upper end of the air cylinder 51 and allowing the lower end of said cylinder to exhaust into the open air. The piston rod of the air cylinder 51 is then driven downwardly to open the casing halves 12 and 13. Actuation of the air cylinder AC₅ acts with the spring S₅ to return the main valve V₅ rightwardly to its position shown in FIGURE 17 thereby allowing air from the main regulator R₂ to flow into the rightward side of the air cylinder 47 and allowing the leftward side of said air cylinder to exhaust into the atmosphere. The pusher 38 is thus retracted from the casing-half area.

Full retraction of the piston rod of the air cylinder 47 (FIGURE 17) moves through suitable mechanical means which may include a cam C₂, the pilot valve V₇ leftwardly against a spring S₇ thereby allowing air from the pilot regulator R₁ to flow to a timing device T₂ and to the air cylinder AC₆. It will be seen that the pilot valve V₇, the spring S₇, and the cam C₂ comprise the air switch 59 of FIGURE 1. The air cylinder AC₆ is connected to the main valve V₈ and moves same leftwardly against the spring S₈, thereby allowing air from the main regulator R₂ to flow to the upper end of the air cylinder 58 and allowing the lower end of said air cylinder to exhaust into the atmosphere. The trap device 53 (FIGURE 5) is thereby caused to advance a load of packing material into the casing halves 12 and 13.

The timing device T₂ (FIGURE 17), consisting of a ball check valve and restrictive orifice in parallel, restricts the flow of air therethrough into the air cylinder AC₇. Timing out of the timing device T₂ allows the air cylinder AC₇, with the spring S₈ to return the main valve V₈ rightwardly to its position shown in FIGURE 17 whereby air from the main regulator R₂ is allowed to flow into the lower end of the air cylinder 58 and whereby the upper end of the air cylinder 58 is allowed to exhaust into the atmosphere. The trap device 53 is thus retracted to its position within the hopper 50 as shown in FIGURE 5.

OPERATION OF FORMS SHOWN IN FIGURES 1 TO 8 AND 17

Assuming for purposes of illustration that the device thus far described is to be used for packing small and flexible plants such as carnations into peat moss and then into a paper bag, the hopper 50 will be appropriately supplied with peat moss, a supply of such plants will be placed on the table 1 at one side of the guide casing 18 and a supply of bags is placed on said table on the other

side of said guide casing 18. The operator will in starting the machine place by hand a suitable supply of peat moss in the open casing halves 12 and 13 (FIGURE 3) and then lay a plant on the upper surface of said peat moss with the roots to the left of the end plate 11 and the upper part of the plant extending through the slot 39 and lying to the right of said end plate 11. The operator then places the mouth of the bag over the guide cylinder 34. The operator then depresses the push buttons PB₁ and PB₂ (FIGURE 17) opening the series pilot valves V₁ and V₂ to allow the air cylinder AC₁ to move the main valve V₃ to its leftward position at or after which point the operator may release said push buttons. Since the air cylinder AC₁ acts quickly, only a momentary depression of said push buttons is required of the operator. Upon release of the push buttons PB₁ and PB₂, the air cylinder AC₁ exhausts into the atmosphere thus readying it for another cycle of operation and the main valve V₃ maintains its leftward position. The main valve V₃ in its leftward position so actuates the air cylinder 51 as to raise the yoke 16 (FIGURE 1) and effect a closure of the casing halves 12 and 13. As said yoke reaches the upward end of its stroke it actuates the pressure fluid switch 60 and energizes the cylinder 47. This effects leftward movement of the pusher 38 and thereby drives the packing material which has now become closed around the roots of the plant through the guide cylinder 34 and into the container C. Preferably, said pusher will extend on through and beyond said guide cylinder 34 so that the container C is pushed off said guide cylinder 34 and the packing thereof is completed subject only to such further processing as may be desired, such as tying of the container C, placing it into a box or other operations as desired.

As the pusher 38 begins to move toward the casing halves 12 and 13, the pressure fluid switch 59 is released which (FIGURE 17) allows the pilot valve V₇ thereof to be moved by the spring S₇ to its rightward position whereupon the air cylinders AC₆ and AC₇ exhaust freely into the atmosphere. Free airflow from the air cylinder AC₇ is allowed by the orientation of the timing device T₂. The pilot system of the valve V₈ is thus made ready for actuation.

Where the device is intended to fill relatively small pots P in place of the sack-type container C a pot P may be placed over the end of the guide cylinder 34 and held in place, usually by hand, as indicated in broken lines in FIGURE 7. The apparatus and the rest of the operation of the device remain the same as above described.

The pusher 38 continues to the end of its stroke and then maintains its position thereat, momentarily, until the timer T₁ (FIGURE 17) times out. The pilot valve V₆ then is opened by the air cylinder AC₃ to permit actuation of the air cylinders AC₄ and AC₅. The air cylinder AC₄ then adjusts the main valve V₃ rightwardly to move the piston rod of the air cylinder 51 downwardly which results in the opening of the casing halves 12 and 13 and allows the air cylinders AC₂ and AC₃ to exhaust freely into the atmosphere. Simultaneously, the air cylinder AC₅ and the spring S₅ move the main valve V₅ rightwardly, reversing the air pressure in the air cylinder 47 and causing same to retract the pusher 38. As the pusher 38 reaches the limit of its movement away from the casing halves 12 and 13, it actuates the switch 59 which energizes the cylinder 58 and causes the shuttle 57 to move rightwardly as seen in FIGURE 5. This carries a quantity of material within the trap chamber 56 rightwardly out of the opening 54 adjacent the bottom of the hopper 50 and drops it into the casing halves 12 and 13.

After a preselected period of time has elapsed, the timer T₂ (FIGURE 17) times out, thereby allowing the air cylinder AC₇ and the spring S₈ to move the main valve V₈ rightwardly, thereby reversing the air cylinder 58 and retracting the trap 53 (FIGURE 5) into the hopper 50. A cycle of operation is thus completed and further cycles may be undertaken in the manner suggested hereinabove.

It will be recognized that by this mechanism a single operator can pack a large number of items of nursery stock in a relatively short time but that the device may be changed readily with respect to the type of plant being packed, the type of packing material being used, and the type of container into which the packing is placed all without modification of the apparatus. Hence, this machine is particularly suited for handling relatively small quantities of a diversity of products and packing situations and it will accomplish such packing both accurately and efficiently. Further, the machine as described is of low cost both to build and maintain but it will be recognized that the degree of automation applied thereto may be widely varied. For example, any or all of the air cylinders 47, 58 and 51 may be eliminated and the operations performed thereby may be readily carried out by hand upon the application of suitable handles to the rod 41 and shuttle 57 and yoke 16, respectively. Suitable conveyors may be provided both for supplying plants and containers to the machine and for removing packed containers away from the machine. Hence the machine, though simple, is extremely versatile, and the single, simple, base machine may be widely adapted to many specific packing conditions and requirements.

FIGURES 9 TO 16

Where it is desired to pack items in a sufficiently large number to justify the cost of fully automated production equipment, the apparatus above described is readily adaptable thereto.

Referring first to FIGURE 12, there is shown a single unit of the invention modified for multiple use. The apparatus here shown is generally similar to that shown in FIGURES 1 to 7, inclusive, with a few modifications, which will be readily evident. The majority of the parts are identical with those already described in connection with FIGURES 1 through 7 and hence these parts are denoted by the same numbers as are used in FIGURES 1 to 7 accompanied by the letter "a" and they will be understood as identical with the corresponding parts already described and no further description thereof will be needed. Referring to the changes, however, it will be noted that the table 1 is somewhat shortened and now appears as a plate 61 having hinge lug means 62 (FIGURE 15) at its opposite sides for connecting with other similar plates to form a continuous articulated belt. The means for operating the rod 41a is a roller 63 carried thereby which bears against suitable cam tracks 101 and 102 described further hereinafter. The vertically movable plunger 24a carries at its lower end a roller 64 which also operates in response to a suitable cam track 100. Also the guide cylinder 34a is shown as somewhat lengthened for automatic retraction of the bag C thereon as required during the cycles of operation. The major difference, however, between the hand single-station device above described and the multiple-station device herein being described is the presence of the receptacle unit generally indicated at 71 (FIGURES 9, 12 and 13). Here a separate plate 72, likewise carrying side extending lugs 73 for articulating same into a continuous belt structure, is provided for supporting the receptacle unit 71 in a predetermined relationship with respect to the parts associated with and supported by the plate 61. A receptacle 74 is mounted at 76 (FIGURE 9) pivotally on a pair of uprights 77 and 78 (FIGURE 16), said uprights being rigidly fastened to the web of the inverted channel member comprising the base 75. Said receptacle 74 is in this embodiment shown as being of cylindrical shape but it may be of any desired size and shape appropriate to receive the packed container from the guide cylinder 34a. A plunger 79 (FIGURE 13) extends through the receptacle 74 through a suitable opening in the base of said container and is fixed to a base portion 82 defining a shoulder with respect to said rod 79 for limiting

rightward (as seen in FIGURE 13) movement of said rod. A plate 83 is affixed to the other end of said rod for defining a reciprocal bottom for the receptacle 74. Suitable resilient means 84 are provided between the rod base 82 and the base 75 for constantly urging said rod base 82 rightwardly. A mounting bracket 86 is mounted on said rod base 82 and carries a cam follower 87.

The parts are arranged as hereinafter set forth in more detail so that the resilient members 84 will normally maintain said receptacle 74 in a horizontal position on the limiting support 85 as shown in FIGURE 13 and appropriate actuation of the cam follower 87 will pivot the receptacle on the pivot support 76 and move it into the position shown in FIGURE 9.

FIGURE 14 shows a modified receptacle structure 74 which may be used for loading non-flexible containers such as the pot P shown therein. The modification required is a simple one and includes the removal of the aforementioned plate 83 from the end of the plunger 79. A pot container 132 into which the pot P snugly but extractably fits, fits snugly but slidingly into the mouth of the receptacle 74 and in its normal position therein extends a suitable distance beyond the mouth of the receptacle 74 so that when the receptacle 74 is horizontally positioned as in FIGURE 13, the rim of the pot P will be spaced only slightly from the discharge end of the guide cylinder 34a. A spring 133 tends to maintain the pot container 132 in its aforesaid normal position as shown in FIGURE 14. The rod 79 functions to force and partially exit the pot P from the pot container 132 at the end of the packing cycle as herein-after discussed.

Turning now to the manner in which these units are arranged together for automatic operation, attention is directed to FIGURES 10, 11 and 12 wherein the apparatus is shown somewhat schematically for ease in understanding the principles thereof but nevertheless in sufficient detail to enable those skilled in the art to practice the invention.

A plurality of plates 61 as described are coupled together to form an articulated belt 91 which is arranged over suitable drive rollers of which one end of a pair is shown at 92 and 93 and one of a similar pair at the other end is indicated at 93a. Said drive rollers revolve in bearings indicated at 135, 136, 137 and 138. A hopper 96 is provided for introducing packing material into the casing halves 12a and 13a. Said hopper 96 may be operated so as to open and close in timed relation to the appearance of a pair of casing halves 12a and 13a under same or the hopper 96 may be preferably permitted to discharge continuously. Said continuous discharge requires that shedders 131 as seen in FIGURE 11 be placed between the outward edges of the unclosed casing halves 12a and 13a if peat moss is not to be wasted or alternately, said casing halves will be placed substantially touching each other from one unit to the next as shown in FIGURE 15. Said hopper 96 may as shown in FIGURE 15 contain an agitator 121 driven by means not shown and may be opened by means of a door 122. A knife means 123 may be used to sweep excess peat moss from filled casing halves toward casing halves being filled.

At 97 there is indicated schematically the presence of means for placing a container C such as a plastic or paper bag in place on the guide cylinder 34a. The means 97 may be an automatic device or it may be a workman applying said receptacles by hand onto the guide cylinders 34a as same appear successively adjacent the station 97.

A substantially similar indication appears at 98 with respect to means for placing a plant in position on the packing material carried by the open casing halves 12a and 13a. This may be carried out automatically or same may be done by a workman occupying the approx-

imate position shown by the station 98 and placing said plants in position by hand.

A suitable cam track 100 is provided under the belt 91 for engaging the successive rollers 87 at appropriate times and moving the yokes 16a upwardly for closing the casing halves 12a and 13a together when desired and permitting same again to open when desired. A pair of cam tracks 101 and 102 are provided alongside of the belt 91 for receiving the successive rollers 63 which drive their associated pushers 38a and cause each said pusher 38a to enter into a cylinder, defined by casing halves 12a and 13a when same are closed together, for driving the packing material and plant contained therein through the guide cylinder 34a and into the container C held thereon. In order to minimize the number of ram units (each comprising in part a pusher 38a, a slider 43a and a controller 63) needed, it may be desirable, instead, to provide a ram unit for co-operation therewith on each of the plates 61 whereby a plurality of ram units may be provided separately from the units carrying the casing halves 12a and 13a. To this end, said ram units may be mounted on separate mounting plates 103 and said plates may be articulated together for forming a separate belt 104. Said belt 104 will, however, be mechanically interlocked with the belt 91 in order that the pushers 38a will be aligned properly with successive casing halves 12a and 13a when same are closed to form a packing cylinder. The belt 104 is here shown as mounted on suitable drive rollers one of which is shown at 143 (FIGURE 12); said rollers are mounted in bearings indicated at 136, 144, and 145 (FIGURE 10).

The receiving units characterized by the receptacles 74 and the bases 72 upon which said receptacles are mounted, are also articulated together to form a belt 111. This is mounted upon suitable rollers one of which is shown at 112 (FIGURE 12) which are mounted in bearings 140 and 141 and are driven in any convenient manner, not shown, but wherein the driving is rigidly interlocked with the driving of the belt 91 in order that said successive receptacles 74 will be coaxial with successive ones of the guide cylinders 34a. A pair of spaced cam tracks 116 and 117 are provided for engaging the successive cam followers 87 for rotating the receptacle units 71 from their FIGURE 13 positions to their FIGURE 9 positions.

Thus the operation of the individual units is substantially the same as that above described in connection with the single-station machine. However, the operation of the automatic machine will be reviewed further in the interest of insuring a complete understanding of this aspect of the invention.

As seen in FIGURE 10, each of the successively arranged casing units first enters a given cycle at the station I where same is on the upper side of the belt 91 and the casing halves 12a and 13a are open ready to receive a quantity of packing material. Here an appropriate container C is placed on the guide cylinder 34a in the same manner as above described in connection with the single-station unit. Said casing unit then passes under the hopper 96 at Station II and is filled to a degree dependent upon the rate of discharge of said hopper 96. At Station III the plant is placed, again with the root portion thereof over the packing material and the upper portion extending through the slots 39a of the pushers 38a. At Station IV the cam follower 64 rides up on the cam 100 and effects a closing of the casing halves 12a and 13a. This is followed at Station V by commencement of the rise of the cam 101 whereby the pusher 38a is driven into the closed casing halves 12a and 13a to drive the packed material and plant contained therein into and through the guide cylinder 34a and the container C is ranged thereon. At Station VI the pusher 38a is partway through the guide cylinder 34a and the container C is shown as having attained a position partway into the receptacle 74. At Station VII the container C is all the way into the receptacle 74. Beginning at Station VIII the cam 102 effects a withdrawal of the pusher 38a from the

receptacle 74 and the cams 116 and 117 engage the roller 87 and commence turning the receptacle 74 upwardly into the position shown in FIGURE 9. By this procedure the reason for tipping receptacle 74 up is so that the plant will be lifted away from pusher 38a at the end of its stroke and will not be pulled back with it. This turning is completed at Station IX at which point any desired further processing of the package may take place, such as removing it manually or automatically from said receptacle, placing it in a further box or package, placing an identifying band thereon or other procedure as desired. It will be noted that the cam tracks 116 and 117 may be so designed as to effect, through the rod 79 and plate 83, the ejection of the sack C from the receptacle 79 automatically at or beyond Station IX.

In the meantime, commencing at Station VII the cam 100 lowers at 100a and permits the yoke 16a to drop and thereby open the casing halves 12a and 13a. Said casing halves now return on the under side of the belt 91 to Station I as above described and the cycle is ready to repeat.

The operation involved when pots P are to be filled automatically is essentially the same as that employed for filling bags C but with the following changes. The bagger 97, rather than placing a bag C on the guide cylinder 34a at Station I, may be employed to place a pot 25 P in the pot container 132 first as a suitably modified receptacle 74 appears on the upper side of the belt 111. Said pot P now being closely placed to the discharge end of the guide cylinder 34a at Station IV receives the peat moss and plant contained therein. It will be noted that close placement of the pot P to the discharge end of the guide cylinder 132, together with the somewhat compressed state of the peat moss resulting from its movement by the pusher 38a will reduce spillage to negligible amounts. Overshoot of the pusher 38a is absorbed by the spring 133. At Station IX the rod 79 propelled by the cams 116 and 117 engages the bottom of the pot P from the pot container 132 and said pot P may now be lifted from the receptacle 74 and placed in a further box or package or disposed of in any other way desired.

Although particular preferred embodiments have been described above for illustrative purposes, it will be recognized that variations or modifications of such disclosure which lie within the scope of the appended claims are fully contemplated.

What is claimed is:

1. A packaging device, primarily for nursery stock, comprising in combination:

a pair of substantially horizontal hemicylindrical casing halves and hinge means hingedly connecting said casing halves for pivotal movement toward and away from each other about a substantially horizontal hinge axis which extends lengthwise of said casing halves and which is located adjacent the lower lengthwise edges of said casing halves;

closure control means for effecting pivotal movement of said casing halves between an open position in which said casing halves open upwardly and a closed position in which said halves face each other and define a generally cylindrical packing space; reciprocable ram means positioned adjacent one longitudinal end of said casing halves and aligned with the packing space defined by said casing halves when they are in said closed position and means for effecting reciprocation of said ram means into and out of said packing space so that when the casing halves are in their open position packing material can be deposited therein and then said casing halves can be moved to their closed position in order to shape said packing material into a generally cylindrical shape, following which said ram means may be moved lengthwise through said packing space to discharge the packing material therefrom.

2. A packaging device according to claim 1, in which

5 said closure control means is disposed below said casing halves.

3. A packaging device according to claim 2, in which said closure control means includes a vertically reciprocable member and means for moving said member upwardly in order to move said casing halves to said closed position and downwardly in order to effect movement of said casing halves to said open position.

10 4. A packaging machine primarily for nursery stock, comprising the combination:

a pair of hemicylindrical casing portions and hinge means hinging same together for opening and closing movement with respect to each other;

15 means supporting said casing portions in a substantially horizontal upwardly opening position when said portions are in open condition;

a guide tube and alignment means for supporting same coaxially with respect to said casing portions when same are in closed position;

20 a ram and driving means supporting same for reciprocable movement centered on an axis coincident with the axis of said casing in closed position;

whereby packing material and the plant may be placed on the casing portions when same are open, and after same are closed said ram may move through the confined zone formed thereby and drive said packing material and the plant held therewithin into and through said guide tube; and

25 the end of said guide tube being adapted for supporting a container into which the packing material and plant may be impelled.

30 5. The device defined in claim 1 wherein said closure control means comprises a generally Y-shaped member positioned below said casing halves with the branches of 35 said Y-shaped member engageable respectively with each of said casing halves and means for effecting vertical movement of said Y-shaped member, whereby upward movement will effect closing of said casing halves and downward movement of said Y-shaped member will permit said casing halves to open.

35 6. The device defined in claim 5 including also means positively urging opening movement of said casing halves.

40 7. The device defined in claim 1 including also a receptacle holder adapted in a first position for holding a receptacle into which said packing material is to be packed adjacent and in filling relationship to said casing halves and means effecting movement of said receptacle holder into a second position for further manipulation of said receptacle following placement of said material therein.

45 8. The device defined in claim 1 including also a receptacle holder pivotally supported with respect to said casing halves for movement between first and second positions, said first position being substantially coaxial with said casing halves when they are in said closed position and said second position being at an angle with respect thereto and means effecting alternate movement of said receptacle holder between said first and second positions.

50 9. The device defined in claim 1 including also a receptacle holder pivotally supported with respect to said casing halves for movement between first and second positions, said first position being substantially coaxial with said casing halves when they are in said closed position and said second position being at an angle with respect thereto, and means operable in synchronism with said ram for effecting alternate movement of said receptacle holder between said first and second positions.

55 10. The device defined in claim 1 having also receptacle holder means which includes a frame member pivotally supported with respect to said casing halves, a slidably receptacle holder supported on and by said frame member and movable thereon toward and away from the point of such pivoting and resilient means urging said receptacle holder away from said point of pivoting, the pivoting of said frame member providing for movement

13

thereof into a first position substantially coaxial with said casing halves when they are in said closed position and into a second position at an angle with respect thereto, whereby when said frame member is in its first position and a receptacle is positioned in said receptacle holder, 5 said ram means in urging said material from said casing halves into said receptacle will urge said receptacle against said resilient means.

11. The device defined in claim 1 including a plurality of pairs of further substantially similar casing halves and hinge means connecting said pairs of casing halves together and means arranging said pairs of casing halves for successive presentation of all of said pairs of casing halves to a first station, means at said first station for supplying packing material to said pairs of casing halves and means automatically operative successively on said pairs of casing halves for causing them to be in open position at said first station and for subsequently assuming a closed position. 10

12. The device defined in claim 11 including also a plurality of guide tubes and alignment means, said alignment means maintaining alignment of at least one of said guide tubes with a closed pair of casing halves at a second station; 20

ram means and means maintaining said ram means coaxial with said guide tube and said casing halves at said second station; whereby packing material may be placed on said successively appearing casing halves at said first station, a plant placed thereon and said casing halves closed at a point immediately following said first station and said ram will drive said packing material through said guide tube and into a receptacle at said second station and said procedure will be repeated successively as the casing halves are successively presented to said stations. 25

13. An automatic packaging machine primarily for nursery stock, comprising the combination:

a plurality of pairs of hemicylindrical casing members and hinge means hinging same together for opening and closing movement with respect to each other and first endless belt means supporting said casing halves in substantially horizontal position when said members are in open condition and arranged for successive presentation to a first station; 40

means at a second station for closing casing halves successively and for holding same closed at a third station and thereafter permitting said casing members to open; 50

a plurality of guide tubes and means including a second endless belt for supporting a plurality of said guide tubes, said first and second endless belts being arranged with respect to each other so that said casing members and said guide tubes will be arranged coaxially with respect to each other at least at said third station; 55

a plurality of ram units and means including a third endless belt for arranging said plurality of ram means for successive presentation to said third station and alignment at said third station with said casing members and said guide tube; 60

14

means effecting reciprocation of said ram while maintaining said alignment; whereby packing material may be placed in said casing members at said first station and the plant to be packed therein may be placed on said packing material immediately after said first station and a ram may be actuated to drive packing material with a plant therein at said second station from the one of said casing members located thereat at a given moment through the guide means aligned therewith and into a receptacle.

14. The device defined in claim 13 including a plurality of reciprocable holders and means including a fourth endless belt for supporting same for successive presentation to, and alignment with, said guide means at said second station. 15

15. A packing device primarily for nursery stock, comprising in combination:

a base;
a pair of hemicylindrical casing halves hinged together along respectively adjacent edges thereof;
a pair of end units closing the ends of said casing members in both open and closed positions thereof and closure control means for effecting opening and closing of said casing halves;
openings through said end units coaxial with said casing halves when same are in their closed position;
a guide tube affixed to one end unit coaxial with the opening therein and adapted for receiving material from within said guide tube into a package held adjacent the end thereof; and
ram means reciprocably arranged and centered on the line coaxial with the opening in said other end unit and with the casing halves when same are in their closed position;
means effecting reciprocation of said ram means;
control means for automatically sequencing an operating cycle of said foregoing named parts, said control means including means providing a pause following the working stroke of said ram means and before the retraction thereof;
whereby said casing unit may be opened for receiving packing material and a plant therewithin and when same is closed said ram unit may operate to push such packing material and the plant contained therewithin out from said casing, into said guide unit and thence into said receptacle and time will then be provided for the operator to remove the receptacle away from the ram means to prevent the packing material from following the ram means on its return stroke.
